HIGH-SPEED DIRIGIBLE

Frank A. Petry, 1615 Armacost Ave., Los Angeles, Calif.

Filed June 1, 1965, Ser. No. 85,526

Term of patent 14 years

(Cl. D71—1)

Fig. 3

Fig. 4

FIG. 1 is a front perspective view of a high-speed dirigible, showing my new design;

FIG. 2 is a bottom plan view thereof;

FIG. 3 is a side elevational view thereof; and

FIG. 4 is a front elevational view thereof.

I claim:

The ornamental design for a high-speed dirigible, substantially as shown.
